Inventor:

W. E. Bird

United States Patent Office.

W. E. BIRD, OF WEST BRIDGEWATER, MASSACHUSETTS.

Letters Patent No. 72,592. dated December 24, 1867.

IMPROVED WASHING-MACHINE.

The Schedule referred to in these Letters Patent and making part of the same.

TO ALL WHOM IT MAY CONCERN:

Be it known that I, W. E. BIRD, of West Bridgewater, in the county of Plymouth, and State of Massachusetts, have invented certain new and useful Improvements in Washing-Machines; and I do hereby declare that the following is a full and exact description thereof, reference being had to the accompanying drawings, and the letters of reference marked thereon.

The nature of my invention consists in an improved arrangement for attaching to an ordinary wash-tub adjustable levers and a dasher or plunger, the whole forming an improved washing-machine.

To enable others skilled in the art to make and use my invention, I will proceed to describe its construction and use. In the drawings—

Figure 1 represents in perspective a view of an ordinary wash-tub with my invention attached.

Figure 2 is a vertical section of the same.

Figure 3 is a plan of the same.

B, figs. 1 and 2, is a clasp or clamp embracing the side of the tub, and is secured to the same by means of the clamp-screw C, fig. 2. To the upper end of this clamp I attach a lever, H, by means of the joint D. K is a standard attached to the opposite end of the lever H by the joint P, the standard K serving to operate the plunger or dasher L, figs. 2 and 3. About midway of the lever H, I attach, by means of the pivot N, a shield or disk, M, the said shield having upon its upper edge two sockets S S, through which the lever or handle R is passed. In the lower part of the shield M are perforations a a, &c., through which a pin, O, figs. 1 and 3, passes. As the pin O also passes through a hole in the lever H, it holds the shield N, and, consequently, the lever or handle R, in position. To change the angle which the handle R makes with the lever H, I have simply to remove the pin O, and, having revolved the handle R around the centre-pin N until it assumes the desired position, that indicated by R', for instance, replace the pin O. The end of the lever H has two projections or stops, h h, figs. 1 and 2, which strike against corresponding shoulders on B, fig. 2, so that when it is desirable to take the clothes out of the tub, the lever H may be raised up and thrown back a little past the perpendicular, and be allowed to rest on the said projections and shoulders.

The advantages that I claim for my invention are, that it is cheap and simple, and when united with an ordinary wash-tub it forms a complete washing-machine, and that the handle R may be made to assume any position desired by the operator.

My invention possesses three desirable features, which I think give it a distinctive character: first, it may be combined with an ordinary wash-tub, and thus form a very convenient and cheap washing-machine; second, the handle or lever by which it is operated may be set at any desired angle, thus making it convenient for the operator; third, by the arrangement of the stops h h, all of the working parts may, when raised up out of the tub, be poised in a convenient position, as shown by the dotted lines in fig. 1. While standing in this position the stops h h will rest against corresponding shoulder on B, and the dasher L is suspended over the tub, so all the drip will fall into the tub.

Having thus described my invention, I will now proceed to set forth my claims.

What I claim as my invention, and desire to secure by Letters Patent, is—

1. The combination of the clamps B, the joint D, and lever H, substantially as described, and for the purpose set forth.

2. The adjustable shield M, in combination with the handle R and lever H; substantially as described, and for the purpose set forth.

W. E. BIRD.
